US0D1040809S

(12) **United States Design Patent** (10) Patent No.: **US D1,040,809 S**
(45) Date of Patent: ** Sep. 3, 2024

(54) **COMBINED KEYBOARD AND MONITOR**

(71) Applicant: **Liling Yu**, Guangdong (CN)

(72) Inventor: **Liling Yu**, Guangdong (CN)

(**) Term: **15 Years**

(21) Appl. No.: **29/927,033**

(22) Filed: **Feb. 2, 2024**

(51) LOC (14) Cl. **14-02**

(52) U.S. Cl.

USPC **D14/392**

CLAIM

The ornamental design for a combined keyboard and monitor, as shown and described.

DESCRIPTION

FIG. 1 is a front, right, and top perspective view of a combined keyboard and monitor, showing my new design; FIG. 2 is a rear, left, and bottom perspective view thereof; FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof; and,

FIG. 9 is a front, right, and top perspective thereof, illustrated in another configuration.

The broken lines in the drawings depict portions of the combined keyboard and monitor and form no part of the claimed design.

1 Claim, 9 Drawing Sheets
